COMMUNICATION SYSTEM

Harry J. Nichols, Dayton, Ohio, assignor to International Business Machines Corporation, New York, N. Y., a corporation of New York

Application December 31, 1934, Serial No. 759,933

14 Claims. (Cl. 234—36.5)

This invention relates to a communication system, and more particularly to a time printing mechanism for printing telegraph systems.

It is the principal object to provide in a very simple and effective manner for the measurement of the time required for the transmission of messages in a printing telegraph system and also to provide for the printing of time indications showing the time of transmission of such messages.

It is a further object to provide a time printing mechanism adapted to print time indications at the beginning and end of a type message directly on the face of the message, such indications showing the time required for transmission.

It is a further object of the invention to provide a method and apparatus whereby the printing at the sending end of a printing telegraph system, in addition to printing time indications on the original of the message, will transmit the proper signals to cause the same indications to be printed on the received copy at the receiving end of the system, so that the original and the received copy each show the elapsed time of transmission of the message.

It is also an object to provide a system for quickly and easily indicating the summation of time required for the transmission of a series of messages, sent either continuously or intermittently.

Other objects and features will be in part obvious, and in part hereinafter pointed out in connection with the following description, the accompanying drawing, and the appended claims.

Certain types of printing telegraph messages are charged for on the basis of the time required for the originating operator to transmit the message. The present practice is for an operator at the control office of the communication company to time the message in the same general manner that long distance telephone messages are timed; or in some cases of large installations, the originating operators stamp each message sheet in an automatic time stamp just before the sheet is inserted in the transmitting printer, and immediately upon withdrawal therefrom. From the time stamps, the time required for transmitting the message is computed for service charge purposes.

In another class of printing telegraph service, called the serial number service, service charges are based on the accumulated time of a series of messages. The invention affords means for the automatic summation of the time of a series of messages.

In accordance with the present invention, each original message may have the time groups printed thereon at the proper points for computation of the time of transmission, and the received copy have printed thereon the identical time groups. Consequently, the possibility for differences as to time charges between the customer and the communication companies is minimized.

A fuller understanding of this invention will be had upon reference to the drawing in which:

In the drawing,—

Fig. 1 shows schematically the circuits and apparatus of a preferred embodiment of the invention;

Fig. 1a is an end view of the clutch actuating mechanism of Fig. 1 shown in the engaged position.

Fig. 1b is similar to Fig. 1a, but shows the clutch actuating mechanism in released position;

Fig. 2 shows a detailed side view in part section of the cyclometer mechanism and decimal switching mechanism schematically indicated in Fig. 1;

Fig. 3 is a sectional view of the mechanism of Fig. 2 taken along the axis 3—3 as indicated;

Fig. 4 is an end elevational view of the mechanism of Fig. 2 as viewed from the right hand end thereof; and

Fig. 5 is a detailed view, in part section, of the "tenths" decimal switch structure of Fig. 2, showing the arrangement of the contacts.

Fig. 6 is a detailed view in part of the sequence mechanism start-stop pawl arrangement.

In the several figures, like characters represent like parts.

Referring now to the drawing, which shows a preferred embodiment of the invention, the timing key TK is mounted on the printer key board (not shown) in the same manner as the printer actuating keys, as for example the numeral keys "0" to "9" inclusive, the "2" and "5" keys only being shown for illustrative purposes. The printer actuating keys operate the printer mechanism (not shown), and also function to transmit printing signals to the receiving printer as indicated by the switch contacts 2', 5', etc. shown beneath the printer actuating keys. The timing key does not actuate the printer mechanism, but functions only to close contacts 10 and thus the local timing circuit. Each printer actuating key is provided with a key solenoid 12, 15, etc. which when energized pulls the key down, thus actuating the printer mechanism. It is assumed that the sending and receiving printers are of identical construction, hence only the apparatus at 55

the sending end is shown. Any desired type of printer and transmission mechanism may be used in connection with the present invention.

The principal elements of the timing mechanism are the drive shaft 20, the sequence switch 30, the clutch 40, the cyclometer 50 and decimal switch 60. Drive shaft 20 is driven by a constant speed motor (not shown) which also constitutes the drive means for the synchronous mechanism of the printer. Hence drive shaft 20 rotates at a known speed, which may be assumed for illustrative purposes as 450 R. P. M. Drive shaft 20 is divided into two sections, namely continuous section 20a and intermittent section 20b. Section 20a is in continuous rotation, while section 20b rotates only when coupled to section 20a by clutch 40, in which case its rotation is the same as that of section 20a. Section 20a is step pivoted in section 20b by a pin and socket bearing 20 or in other preferred manner. Drive shaft 20 is shown broken into sections for clarity in illustration.

Fixed on drive shaft section 20a is a wheel 21 with resilient rim 21a of rubber or the like. Mounted adjacent thereto on parallel shaft 32 is friction cam 33 adapted, when released, to engage wheel 21 and thus to rotate sequence switch 30. Sequence switch 30 is shown cut into two sections in order to clarify the drawing. The sequence switch comprises friction cam 33, sequence cam 33a integral therewith, contacts 34 and 35, and motion control means. Friction cam 33, provided with a knurled edge with a shallow notch at the point normally adjacent wheel 21, is normally held out of engagement with wheel 21 by pivoted pawl member 36 provided with two turned down prongs, one positioned in advance of the other, either one of which can engage pin 33c mounted in the upper face of friction cam 33, depending upon the position of the pivoted pawl member. Accelerating spring 37 bears against pin 33d mounted in lower face of cam 33 and tends to rotate cam 33 in the direction indicated by the arrow. Pawl 36 is actuated by release magnet 39, whose armature 39a is pulled in when release magnet 39 is energized, oscillating pawl 36 by means of link 39b.

The operation of sequence switch 30 is as follows: When timing key TK is depressed, contacts 10 are closed, and the local timing circuit energizes release magnet 39. The circuit may be traced from positive battery, via contacts 10, through winding 39 and return to negative battery. Armature 39a pulls in, pulling pawl 36 to the right as viewed. Pin 33c is thus released, freeing friction cam 33 whereupon accelerating spring 37 rotates cam 33 into engagement with wheel 21. Cam 33 is rotated by wheel 21 almost an entire revolution, whereupon pin 33c is stopped against one or the other of the prongs of pawl 36, depending upon whether timing key TK is released or held. At this point cam 33 is free of wheel 21, and accelerating spring 37 has been reset. Assuming that timing key TK has been held, pin 33c will strike the extended prong 36a of detent 36; upon release of timing key TK, release magnet 39 is deenergized, armature 39a is pulled away by tactile spring 39c, and pin 33c drops back against the short prong 36b of pawl 36, restoring initial conditions. Thus drive cam 33 makes but a single revolution for each actuation of timing key TK, irrespective of the time TK is held depressed. During the revolution of friction cam 33, sequence cam 33a closes contacts 34

and 35 in proper sequence and with the proper interval between closures.

Referring now to Figs. 1a and 1b, as well as Fig. 1, fixedly mounted on drive shaft section 20a is fixed flange 41 of positive clutch 40, while movable flange 42 is carried on a sleeve slidable axially on drive shaft section 20b and secured against rotation thereon by pin 20c, or other preferred means. Throw out pin 42a is mounted in flange 42 in a position to be engaged by trip lever 43, which latter is fixed on rock shaft 44. Fixed on one end of rock shaft 44 is shift plate 44a with studs 44b and 44c mounted diametrically as regards the axis of shaft 44, as clearly shown in Figs. 1a and 1b. A cover plate 45 is riveted on the heads of studs 44b and 44c, and mounted thereon by stud 45a is spring finger 45b. Shift head 46, which is T-shaped, works between studs 44a and 44b. The free end of spring finger 45b slides in a hole in stud 46a mounted on the stem of shift head 46. Tractile springs 47a and 47b move shift head 46 to the extended position, as shown in Fig. 1a. Jockey spring 48 retains shift plate 44a in its alternative positions. Shift head 46 is actuated by magnet 49, but if preferred, may be actuated by release magnet 39, since both magnets are energized from the same circuit at the same time.

The operation of the clutch mechanism is as follows: Assuming for the sake of illustration that Fig. 1a represents initial conditions, upon depression of timing key TK shift head 46 is drawn to the right as viewed. As indicated, spring finger 45b has previously lifted shift head 46 into engagement with stud 44b, hence as the shift head is drawn to the right, shift plate 44a, rock shaft 44, and trip lever 43 are rotated clockwise. Trip lever 43 releases trip pin 42a, thus enabling spring 20d to engage the clutch faces. Drive shaft section 20b is thus set in rotation by, and at the same speed as, section 20a. Trip lever 43 is moved clear of the path of trip pin 42a as shown in Fig. 1b, and is held in position by jockey spring 48, hence there is no interference with the rotation of the drive shaft. Upon release of TK, shift magnet 49 is deenergized, and tactile springs 47a and 47b return shift head 46 to extended position. The tilting of shift plate 44a during actuation has, however, caused spring finger 45b to exert a downward pressure upon stud 46a, hence the shift head is moved into engagement with stud 44c, as shown in Fig. 1b.

Without further analysis, it will be evident that upon successive draws of shift head 46, trip lever 43 will be moved into alternate positions of release and engagement with trip pin 42a, and will be retained in such positions between shifts by jockey spring 48. When trip lever 43 is moved into engaging position, trip pin 42a strikes the inclined surface at the end of trip lever 43, and the movable flange of the clutch is drawn away from the fixed flange. As soon as the clutch faces are clear of each other, trip pin 42a is stopped against the notch in trip lever 43. For further detailed description regarding the principle embodied in the clutch actuating mechanism just described, reference may be made to U. S. Patent No. 2,049,468, particularly Figs. 5 and 6, which show and describe specifically mechanisms embodying such principles.

It is to be noted that the clutch operation, as well as that of the sequence switch, is produced by tripping action, and proceeds irrespective of the length of time of depression of timing key TK. In the case of the sequence switch, the same

cycle of operations results from each depression of the timing key, while the clutch is alternately released and engaged by successive depressions of the timing key.

5 Referring now to Fig. 2, drive shaft 28b, when coupled to the drive section, drives counter shaft 51 by means of worm 28g and worm gear 51a. Counter shaft 51 is hollow, and rotates on jack shaft 52. Integral with counter shaft 51 is the 10 first cyclometer gear 51b. The first cyclometer gear is a one tooth gear and at one point each revolution meshes with pinion 53a, loose on auxiliary shaft 54. Pinion 53b, integral with pinion 53a, meshes with the second cyclometer gear 55a, 15 which is a ten tooth gear. The third cyclometer gear 55b, integral with gear 55a, is a one tooth gear, similar to 51b, and meshes with pinion 56a. Pinion 56b, integral with pinion 56a, meshes with the fourth cyclometer gear 57 which is a ten 20 tooth gear. Fig. 3, taken through line 3-3 of Fig. 2, thus represents the odd numbered cyclometer gears, while Fig. 4 represents the even numbered cyclometer gears.

The design and operation of cyclometer trains 25 is well known, hence detailed description is not required. It will suffice for an understanding of the present invention to state that in the transfer from one cyclometer gear to the following one, a reduction in speed of 10 to 1 is accomplished, 30 and that the rotation of the gears, except the first gear, is intermittent. For example, the second gear is rotated one tenth revolution each time the single tooth of the first gear engages the pinion, but remains at rest during the remainder of 35 the revolution of the first gear, and so on through the train.

The cyclometer train may be designed to enable the recording of minutes and tenths minutes, or minutes and tens of minutes, or any other 40 desired units of time, such matters being well understood by those versed in the art. By way of explaining the present invention, and as an example, it will be assumed that the time groups to be printed are to represent minutes and tenths 45 of minutes. In this case, the first cyclometer gear should rotate once every tenth minute, or at a speed of 10 R. P. M. Since the main drive shaft rotates at 450 R. P. M., the worm gear should have a ratio of 45 to 1. The second and 50 third cyclometer gears will rotate at 1.0 R. P. M., hence each tenth division will represent tenths of a minute. The fourth cyclometer gear will rotate at a speed of one tenth R. P. M., hence each tenth division will represent one minute.

55 Mounted on the right face of cyclometer gear 55b, but insulated therefrom, as for example by insulator disc 58, is the rotary contactor element 61 of the "tenths" decimal switch. This element comprises a metal cup 61a, and a metal finger 61b mounted thereon by suitable means, such as small rivets. Exterior electrical connection is made to cup 61a by brush 62 bearing on the rim thereon. Brush 62 and all other parts in the electrical circuit are preferably insulated from the 60 frame. Rotary contactor element 63 of the "units" decimal switch, which is similar in construction to element 61, is mounted on the left face of cyclometer gear 57, and connection is made to it via brush 64 in the same manner as 65 before.

The stationary contacts 66 of the decimal switch, ten in number, are mounted in insulator plate 65 in any preferred manner, as for example by moulding in position (See Figs. 2 and 5). 70 Plate 65 is rigidly held intermediate contactors 61

and 63; plate 65 also supports the brush holders for brushes 62 and 64. The connections to stationary contacts 66 and to brush 62, as related to Fig. 1, are indicated in Fig. 5. The same set of contacts are contacted by the two contactor elements, but for clarity in illustration the stationary contacts are shown separately in Fig. 1. Each divisional advance of the cyclometer gear moves a contactor element to the next contact, hence in one revolution of an intermittent cyclometer 10 gear all of the contacts will be connected in circuit in sequence.

Referring again to Fig. 1, the complete operation of the timing mechanism is as follows: Assume that the operator has inserted a sheet 15 of paper in the printer, and having completed the preliminary calling procedure, is ready to type the message proper. The operator then depresses the timing key. This closes contacts 10 and energizes release magnet 39 and clutch magnet 49. 20 Release magnet 39 pulls aside detent 36, releasing friction cam 33 which engages wheel 21 and is set in rotation thereby. Sequence cam 33a closes and releases contacts 34, and thereafter, contacts 35. Contacts 34 close a circuit energizing one of the key solenoids, the selection of which is controlled by the "units" sequence switch. As an example, a circuit may be traced from negative battery via contacts 34, via contactor 33 of the "units" switch, via contact 5, 30 through key solenoid 15, and return to positive battery. Key solenoid 15 is energized, pulling down numeral key "5". This latter action actuates the printer mechanism (not shown) and closes key switch 5' which transmits a printing 35 signal (by means of any desired transmitting mechanism) to the receiving printer, which printer also prints the numeral "5" on the receiving copy.

When contacts 35 are closed a short time later, 40 a circuit through the "tenths" switch is set up which may be traced as follows:—From negative battery via contacts 35, via contactor 61 and contact 2, through winding of key solenoid 12 and return to positive battery. Numeral key "2" is 45 thus depressed, actuating the printer mechanism to print numeral "2" and also transmitting a printing signal to the receiving printer which likewise prints numerals "2". Thus both the original and received copies of the message bear 50 the time group 52, translatable as 5.2 minutes.

Meanwhile, upon the energizing of clutch magnet 49, positive clutch 40 is engaged, and the cyclometer mechanism is started up, advancing the decimal switches as previously described during the transmission of the message proper as 55 above explained, the transmission system may make use of any desired apparatus and method, such as the coded impulse or the synchronous system, as the present invention is not restricted 60 to any particular transmission system.

At the end of the message, the operator again depresses the timing key, and a second time group, corresponding to the position of the cyclometer at this time, is printed on the original and 65 received copies of the message, according to the method just described. Assume that this second time group is 98; then subtracting the first time group 52, it is determined that the elapsed time of transmission is 4.6 minutes, and the time 70 charge for service is thus established. As before, clutch magnet 49 is energized at the same time as the release magnet, but this time the positive clutch is thrown out of engagement, as previously described, stopping the cyclometer train. 75

Between messages, the cyclometer train is not actuated, hence the first time group of the next succeeding message will be the same as the second time group of the prior message. Thus the ac-

5 cumulated time of a series of messages can be obtained by subtracting the first time group of the series from the last time group, each individual message showing its own time of transmission.

For simplicity in description, only two decimal switch groups have been shown. It will be clear, however, that by adding another unit assembly to the cyclometer train, another decimal switch group, and another set of contacts to cooperate with the sequence cam, the range of the mechanism can be extended to record tens, units, and tenths of a minute, or by suitable change in the worm gear ratio or motor speed, hundreds, tens, and unit minutes.

20 It will also be apparent to those skilled in the art that well known setting and set-back devices may be added to the cyclometer train to cause the time groups to represent clock time, or to start each message from zero time. Such variations, 25 following the teaching of the present invention, can be introduced to meet the requirements of particular applications. The general method of using arbitrary time groups herein described for illustrative purposes has the merit of relative 30 simplicity, and is generally to be preferred on that account.

While the methods described herein, and forms of apparatus for carrying these methods into effect, constitute preferred embodiments of the invention, it is to be understood that the invention is not limited to these precise methods and forms of apparatus, and that changes may be made in either without departing from the scope of the invention which is defined in the appended claims.

40 What is claimed is:

1. A system of the character described comprising, in combination, printing control instrumentalities and control means therefor, a cyclometer gear train and actuating means therefor, a plurality of selector means operated and positioned by the said cyclometer gear train thereby selecting certain of said control means, means to render the actuating means effective to rotate the gear train to position the said selector means, 50 and means to render operative those control means for the printing control instrumentalities selected by, and in accordance with, the positioning of the said selector means.

2. A system of the character described comprising in combination, printing control instrumentalities and control means therefor, a cyclometer gear train and actuating means therefor, a plurality of selector means operated and positioned by the cyclometer gear train to select certain of said control means, and a control key, the operation of which controls the operation of certain of the control means for the associated printing control instrumentalities selected by the positioned selector means and simultaneously renders 65 the actuating means effective to rotate the gear train to position the selector means to a different position.

3. A system of the character described comprising, in combination, printing control instrumentalities and control means therefor, a cyclometer gear train and actuating means therefor, a plurality of selector means operated and positioned by the cyclometer gear train to select certain of said control means, a control key, means 70 controlled upon operation of the control key to

render operative the control means selected by the positioned selector means thereby operating the associated printing control instrumentalities, and simultaneously rendering the actuating means effective to rotate continuously the gear train to alter the position of the selector means, and means controlled upon a subsequent operation of the control key to render operative other of said control means selected by, and in accordance with, the altered position of the selector means and simultaneously rendering the actuating means inoperative thereby preventing further positioning of the said selector means.

4. A system of the character described comprising, in combination, printing control instrumentalities and individual control means therefor, a cyclometer gear train and actuating means therefor, a plurality of selector means operated and positioned by the cyclometer gear train, circuits connecting each of the said selector means to the said individual control means, and means to control sequentially the operation of the control means for the printing control instrumentalities in accordance with the positioned selector means so as to energize the associated circuits and control means selected in accordance with the positioning of one of said selector means and then to energize the associated circuits and control means selected in accordance with the positioning of another of said selector means.

5. A system of the character described comprising, in combination, a constantly rotating drive shaft, a cyclometer gear train, normally inoperative clutch means adapted upon operation thereof to couple the said gear train to the said shaft, printing control instrumentalities and control means therefor, selector means controlled and positioned by the gear train to select certain of said control means in accordance with the positioned selector means, and means to render operative the control means selected by the positioned selector means and simultaneously rendering the clutch means operative to alter the position of the selector means.

6. A system of the character described comprising, in combination, a cyclometer gear train and actuating means therefor, said gear train comprising a plurality of gear elements operated at different speed ratios upon actuation of the gear train, printing control instrumentalities and control means therefor, a plurality of selector means, each comprising a series of contacts and a rotary contact element to engage the contacts, which is positioned by an individual gear element in accordance with the positioning of the gear element, circuits to connect the said series of contacts to the said control means, and means to render operative the control means selected by the selector means and simultaneously to render the said actuating means operative so as to alter the positioning of the contact elements thereby changing the selection of the control means to be effected.

7. A system of the character described comprising, in combination, a cyclometer gear train and actuating means therefor, said gear train comprising a plurality of gear elements operated at different speed ratios upon actuation of the gear train, printing control instrumentalities and control means therefor, a plurality of selector means, each of which is adapted to be positioned by an individual gear element to select certain of the control means in accordance with its position, and a control key, the first operation of which is effective to control the operation of the

cyclometer gear train to alter the position of the selector means and upon a subsequent operation of the control key to control the operation of the cyclometer gear train so that the selector means 5 maintain the selection of the control means in accordance with the said altered position.

8. A system of the character described comprising, in combination, printing control instrumentalities and control means therefor, a cyclometer gear train and actuating means therefor, a plurality of selector means adapted to be positioned by said cyclometer gear train to select certain of said control means in accordance with the setting thereof, and a control element, the 10 operation of which is effective to render the cyclometer gear train operative to alter the setting of the selector means and upon a subsequent operation of the control key is effective to render the cyclometer gear train inoperative whereby 15 the selector means maintain the selection of the control means in accordance with the altered setting of the selector means.

9. A system of the character described comprising, in combination, a constantly rotating shaft, time indicating control mechanism and selector mechanism to control the operation of said time indicating control mechanism, normally inoperative clutch mechanism adapted upon operation thereof to control the operation of the selector mechanism by said shaft, and control means, the operation of which renders the time indicating control mechanism operative to indicate time indications in accordance with the setting of the selector mechanism and also renders 30 the clutch mechanism operative to control the operation of the selector mechanism thereby altering its setting, and upon a subsequent operation of the control means renders inoperative the clutch mechanism preventing further setting of the selector mechanism and also rendering the 35 said time indicating control mechanism operative to indicate time indications in accordance with the altered setting of the selector mechanism.

10. A system of the character described comprising, in combination, time indicating control 40 mechanism, settable selector means adapted to control selectively the time indicating control mechanism in accordance with the setting of the selector means, control means, means controlled by said control means to render the time indicating control mechanism operative to indicate time 45 indications in accordance with the setting of the selector means, and additional means controlled by said control means to alter the setting of the selector means.

55

11. A system of the character described comprising, in combination, time indicating control mechanism, settable selector means to control selectively the operation of the time indicating control mechanism in accordance with the setting 5 of the selector means, means to position the selector means in a predetermined manner, a control key, and means controlled upon operation of the control key to render the time indicating control mechanism operative to indicate time indications 10 in accordance with the setting of the selector means including means to render the time indicating control mechanism inoperative upon operation thereof irrespective of the length of time 15 the control key remains operated.

12. A system of the character described comprising, in combination, time indicating control mechanism, a plurality of settable selector means to control selectively the operation of the time indicating control mechanism in accordance with 20 the settings of the selector means, means to position the selector means in a predetermined manner, a control key, and means controlled by the said key to render the time indicating control mechanism operative successively in accordance 25 with the individual setting of each of the said selector means.

13. A system of the character described comprising, in combination, time indicating control mechanism, a plurality of settable selector means 30 to control selectively the operation of the time indicating control mechanism in accordance with the settings of the selector means, means to position the selector means in a predetermined manner, a control key, and a plurality of control elements, one for each selector means, controlled by the said key to render the time indicating control mechanism operative successively in accordance 35 with the individual setting of each of the said selector means.

14. A system of the character described comprising, in combination, time indicating control mechanism, settable selector means to control selectively the operation of the time indicating control mechanism in accordance with the setting 40 of the selector means, means to position the selector means in a predetermined manner, a control key and means controlled thereby to render the time indicating control mechanism operative upon each operation of the key to indicate time 45 indications in accordance with the setting of the selector means and rendering the said positioning means effective upon every other operation of the key to alter the position of the selector means.

HARRY J. NICHOLS.

55
